(57) **CLAIM**

The ornamental design for a boat trailer, as shown and described.

DESCRIPTION

FIG. 1 is a front perspective view of the boat trailer in accordance with the design, here shown in a retracted position;

FIG. 2 is a rear perspective view thereof;

FIG. 3 is a side elevational view thereof;

FIG. 4 is a side elevational view thereof, here shown opposite the one in FIG. 3;

FIG. 5 is a top Plan view thereof;

FIG. 6 is a front elevational view thereof;

FIG. 7 is a rear elevational view thereof;

FIG. 8 is a front perspective view of the boat trailer in FIG. 1, here shown in an extended position;

FIG. 9 is a rear perspective view thereof;

FIG. 10 is a side elevational view thereof;

FIG. 11 is a side elevational view thereof, here shown opposite the one in FIG. 10;

FIG. 12 is a top plan view thereof;

FIG. 13 is a front elevational view thereof; and,

FIG. 14 is a rear elevational view thereof.

The uneven-length broken lines immediately adjacent to the solid lines define the bounds of the claimed design and form no part thereof. The even-length broken lines showing the remainder of the boat trailer represent unclaimed subject matter and form no part of the claimed design.
